CLAIM

The ornamental design for the combination ceiling fan and light fixture, as shown and described.

DESCRIPTION

FIG. 1 is a perspective view from below of the combination ceiling fan and light fixture in accordance with my design.

FIG. 2 is a side elevation view of the combination ceiling fan and light fixture in accordance with my design;

FIG. 3 is a bottom plan view of the combination ceiling fan and light fixture in accordance with my design; and,

FIG. 4 is a top plan view of the combination ceiling fan and light fixture in accordance with my design.

The front, rear and side elevation are identical except for the position of the blades.

The blades are shown broken away indicating indeterminate length.
